UNITED STATES PATENT OFFICE

ARTHUR PODMORE, OF HATCH END, MIDDLESEX, ENGLAND, ASSIGNOR TO AMERICAN MACHINE & FOUNDRY COMPANY, OF NEW YORK, N. Y., A CORPORATION OF NEW JERSEY

CUT-OFF MECHANISM OF CIGARETTE MAKING MACHINES

Application filed April 7, 1926, Serial No. 100,407, and in Great Britain May 12, 1925.

The present invention relates to the cut-off mechanism used in cigarette-making machines and the like. In constructions hitherto in use the actual cutting device has been 5 a cutting blade which is rotated at high speed and which is depressed at intervals so that the edge of the blade crosses the path of the wrapped tobacco and so cuts off equal lengths. In order to obtain this dipping motion complicated mechanism is required and it is one 10 of the objects of the present invention to dispense with the dipping motion of the blade. A further object of the invention is to provide improved means for sharpening the 15 knife blade of the mechanism.

According to the invention the cutter is in the form of a disc having a cutting blade projecting therefrom and extending over a portion only of the periphery of the disc. Preferably the blade is adjustably mounted on the disc so that it may be adjusted to take up wear. Further, the cutting edge of the 20 blade is preferably curved eccentrically to the centre of the disc upon which it is mounted, so that a draw-cut action is produced when the apparatus is in operation.

The disc carrying the blade is so mounted that it can be rotated on its centre, the axis of rotation of the blade being always in the 25 same position relative to that of the axis of the tobacco rod to be cut. Further, the blade is reciprocated axially so that at the moment of cutting, the lateral speed of the blade is equal to or is approximately equal to that of the moving tobacco rod. Thus an even cut is assured.

It will be understood that the lateral reciprocation of the knife is such that the cutting blade crosses the path of the cigarette 30 rod in the machine after the rod has moved over the distance necessary for a given length of cigarette.

By this method the cutting off of the cigarette is effected without the dipping of the 35 circular knife.

It will be understood that the cigarette rod passes between the usual ledger plates or the like and that the knife is rotated at such a speed that the interval between two cuts is 40 equal to the length of the cigarette required.

Preferably the blade of the knife extends for substantially one-tenth of the circumference of the circle in which the blade is revolved.

The edge of the knife is preferably automatically sharpened during every revolution by means of an emery wheel or the like arranged at a suitable angle to the blade edge and oscillated during the period of sharpening in such a manner that it produces an edge on the knife which conforms to the cutting edge of the knife, which is eccentric to the centre of the disc. A second emery wheel or the like may also be provided for removing any burr on the opposite side of the 55 knife.

To enable the invention to be fully understood it will now be described by reference to the accompanying drawings in which:

Figure 1 is a side elevation of the cutting mechanism of a cigarette-making machine constructed according to one form of the invention, and

Figure 2 is a plan view thereof partly in section, part of the blade-sharpening mechanism being omitted;

Figure 3 is an end elevation partly in section showing the blade-sharpening mechanism.

As shown, the cutter is in the form of a 80 blade 4, suitably clamped between two discs 5 and projecting beyond the peripheries of the discs, its cutting edge being curved eccentrically to the centre of the discs as in Figure 3.

The discs 5 are extended at 6 to support the blade, similar extensions being provided at 7, diametrically opposite, for balancing purposes. The discs 5 are secured to a splined sleeve 8 mounted on a splined shaft 9, the latter being mounted in fixed bearings parallel to the tube 10 (Figure 1) through which the tobacco rod passes from the cigarette-making portion of the machine in the usual manner. The shaft 9 is driven through a pinion 11 by a pinion 12 mounted on a vertical shaft 13 which in turn is driven through a bevel gear 14 actuated by a main driving shaft 15, the latter being driven in any suitable manner. Mounted on bearings 16 on the sleeve 100

8 is a housing 17 adapted to be reciprocated with the sleeve, but prevented from rotating therewith by a block on its underside (not shown) working between guides 17' on the machine frame. Rods 18 are attached one on each side of the housing and are connected to eccentrics 19 mounted on a cross shaft 20 driven by a bevel 21 on the shaft 9. The eccentrics 19 are preferably adjustably mounted as shown to enable the throw to be varied as desired.

The tobacco rod from the cigarette-making portion of the machine (not shown) passes through the tube 10 (Figure 1) from the mouthpiece 22, a gap 23 being provided through which the blade 4 is adapted to pass to cut the cigarettes, the latter issuing through the tube 10 into a suitable receptacle (not shown).

20 With the above-described arrangement on operation of the main shaft 15, the shaft 9 and blade 4 are rotated and at the same time the blade and housing 17 are reciprocated on the shaft 9, one complete reciprocation 25 preferably corresponding with one revolution of the knife. The parts are so adjusted that during the cutting period, when the blade 4 passes through the gap 23, the lateral speed of the blade is equal to, or approximately equal to that of the cigarette rod, the blade being rotated at such a speed that the interval between the cuts is equal to the length of the cigarette required.

Preferably the blade extends for substantially one-tenth of the circumference of the circle in which it is revolved and the eccentricity of its cutting edge produces a draw-cut action on the tobacco rod.

40 The edge of the blade 4 is preferably automatically sharpened during every revolution by means of an emery or like wheel 24 adjustably mounted in the path of the blade on a lever 25, pivoted at 26 and connected by rod 27 to one arm of a bell crank lever 28 mounted 45 on the housing 17 (Figures 1 and 3). The other arm of the lever 28 is attached to the connecting rod 29, the free end of the rod being anchored to a block 28' slidable on a fixed portion of the machine and controlled 50 by a screw 29' having a handle 30. By operating the screw 29' the length of the connecting rod 29 can be adjusted to lower the wheel 24 as the cutting edge of the knife wears away without stopping the machine.

55 With this arrangement, as the blade 4 revolves and the housing 17 is reciprocated, the wheel 24 is oscillated once per revolution of the blade and is so arranged to wipe the edge of the blade once per revolution. The oscillation of the wheel 24 is such that it sharpens the blade in the correct curve eccentric to the centre of the discs carrying the blade.

A second emery or like wheel 31 may be mounted on the housing 17, as shown, in position to make contact with the side of the blade

opposite to that sharpened by the wheel 24 to remove any burr or roughness. This second wheel moves with the housing but is not oscillated. If desired this second wheel may be oscillated in a manner similar to wheel 24.

In the example illustrated the splines on the shaft 9 and sleeve 8 are shown as parallel to the axis of the shaft. By suitably curving the splines an increased speed at the moment of cutting may be obtained followed by a corresponding retardation after the cut has been made, during which latter period the blade is being sharpened by the wheels 24, 30.

Further, as shown, one knife blade only is employed. Obviously by adjusting the speed of rotation of the clamping discs two or more blades may be used, the timing being such that a cigarette is cut off at the passage of each blade.

It will be understood that the invention may be applied to cigarette-making and like machines of various types.

Having now described my invention what I claim as new and desire to secure by Letters Patent is:—

1. Cut-off mechanism for cigarette machines comprising a driving shaft having its axis parallel to and fixed relatively to the axis of the cigarette tube, an eccentrically edged knife mounted on said shaft, a sharpening member, a pivotally mounted support for said sharpening member and means adapted to oscillate said support to bring the sharpening member into contact with the cutting edge of the knife, the pivoting of said support causing a movement of the sharpening member relatively to the axis of the cutter during the sharpening operation to allow for the varying radii of the eccentric edge of the cutter.

2. Cut-off mechanism for cigarette machines comprising a driving shaft having its axis parallel to and fixed relatively to the axis of the cigarette tube, a housing surrounding said shaft, means for reciprocating the housing along the axis of said shaft, an eccentrically edged knife operatively coupled to said housing so as to reciprocate therewith, a sharpening element, a pivotally mounted support for said sharpening element, means for reciprocating said support parallel to the axis of the shaft and synchronously with the reciprocation of said housing and means for moving said support about its pivot to bring the sharpening element into contact with the cutting edge of the knife.

3. Cut-off mechanism for cigarette machines comprising a driving shaft having its axis parallel to and fixed relatively to the axis of the cigarette tube, a housing surrounding said shaft, means for reciprocating the housing along the axis of said shaft, an eccentrically edged knife operatively coupled to said housing so as to reciprocate therewith, a sharpening element, a pivotally

mounted support for said sharpening element carried by said housing and means for oscillating said support to bring the sharpening element into contact with the cutting edge of 5 the knife.

4. Cut off mechanism for cigarette machines as claimed in claim 3, and having a framework, bearings on said framework for said shaft, a block mounted for movement 10 relative to said framework, means connecting the pivotally mounted support for the sharpening member to said block, and means for adjusting the block relatively to the framework in order to effect adjustment of 15 the sharpening element to take up wear.

5. Cut off mechanism for cigarette machines as claimed in claim 1 and wherein the means for causing the oscillations of the support for the sharpening element include a 20 device adjustable as to length whereby adjustment of the element relatively to the axis of said shaft to take up wear of the knife may be effected.

6. Cut off mechanism for cigarette machines as claimed in claim 2, and wherein the shaft is splined, a splined sleeve engaging the splines on the shaft and carrying said knife, and means operatively connecting the 25 splined sleeve to the housing.

30 In testimony whereof I have signed my name to this specification.

ARTHUR PODMORE.
